UNITED STATES PATENT OFFICE.

EDGAR L. HOLCOMBE, OF MARCELENA, TEXAS.

PIANO.

SPECIFICATION forming part of Letters Patent No. 651,074, dated June 5, 1900.

Application filed November 22, 1899. Serial No. 737,881. (No model.)

To all whom it may concern:

Be it known that I, EDGAR L. HOLCOMBE, a citizen of the United States, residing at Mar-
celena, in the county of Wilson and State of
5 Texas, have invented a new and useful Piano,
of which the following is a specification.

This invention relates to pianos in general, and more particularly to that class in which the strings are vibrated through the medium
10 of a bow, as in a violin, instead of being struck with hammers in accordance with the usual method, one object of the invention being to produce a construction in which the strings will be successively presented to the bow as
15 the keys are successively depressed and in which any number of strings may be simultaneously presented to the bow for the striking of chords.

A further object of the invention is to pro-
20 vide means for moving the strings of the treble bodily into engagement with the bow and to provide other details for the production of a practical and efficient instrument.

In the drawings forming a portion of this
25 specification, and in which similar numerals of reference designate like and corresponding parts in the several views, Figure 1 is a perspective view showing the exterior of a piano constructed in accordance with the
30 present invention. Fig. 2 is a section on line 2 2 of Fig. 4 looking to the left and including the keyboard and adjacent parts. Fig. 3 is a section on line 2 2 of Fig. 4 looking to the right and showing the keyboard, the keys, and
35 the connections between the keys and a slide-
able spring-supporting frame. Fig. 4 is a vertical section showing portions of the mech-
anism of the piano and taken through the
40 keys directly in the rear of the front board of
the piano. Fig. 5 is a detail perspective view showing a key and the mechanism connected therewith for holding a corresponding string or group of strings out of contact with the bow. Fig. 6 is a detail perspective showing
45 the bow and its driving-drum and illustrating also a portion of the reciprocating rod for moving the bow to vary its pressure against the strings and change the volume of sound. Fig. 7 is a detail view showing the gearing for
50 driving the bow-supporting drum at one end of the bow. Fig. 8 is a view, partially in sec-

tion and partially in elevation, showing one of the movable frames which support the treble strings and the means for holding it projected. Fig. 9 is a perspective view showing the means for operating the bar shown in Fig. 6 to move the bow toward and away from the strings. Fig. 10 is a perspective view showing the operating-pedal and its connections for rotating the crank-shaft shown in Fig. 7. Fig. 11 is a perspective view showing the means for starting the crank-shaft shown in Fig. 7 to throw it off its dead-center. Fig. 12 is a diagram showing the method of construction of the bow. Fig. 13 is a diagram showing the method of assembling the hairs of the bow.

Referring now to the drawings, 15 represents the casing of the instrument, which comprises bottom 16, sides 17 and 18, a top 19, and a back 20. In the back of the casing is disposed a sound-board 21, having a string-plate bridge 22, over which is stretched a plurality of strings 23 in the usual manner and which strings form the base and the middle 75 register of the instrument. The strings of the high treble are each supported upon a rectangular frame 24, at the upper and lower ends of which are disposed tuning-pegs 25 and 26, to which the string is connected, the 80 string being passed over a bridge 27 upon the front piece 28 of the frame and being braced by a sounding-post 29, extending from a point beneath the bridge to the rear portion 30 of the frame, this rear portion being removably 85 connected by means of screws or bolts, as shown, and to permit the insertion of the upper and lower bars of the frame through openings 31 and 32 of the sound-board 21 and permit the passing of the sounding-post 29 90 through the perforation 33. After the frame has been thus applied the back bar or piece 30 is secured in place. The strings 23 have a tendency to lie straight from one bridge to the other of the sounding-board and are nor- 95 mally held pressed back in the manner pres-
ently explained. The frames 24 are adapted to be projected forwardly by means of spring-
plates 34, fixed rigidly thereto and having
slidable bearing at their rear ends against the 100 outer face of the sound-board, as shown in Fig. 8.

When the strings 23 and the treble-strings 35 are projected forwardly, they engage a bow, which is in the form of a belt 36, mounted upon drums 37 and 38. One of these drums 5 is journaled between the arms of a U-shaped hanger 39, the stem of which passes outwardly through the end 17 of the casing and is threaded for the engagement of a thumb-nut 40, through the medium of which the hanger may 10 be drawn outwardly or may be permitted to pass inwardly to vary the tension of the bow. The drum 37 at the opposite end has its shaft 41 journaled in bearings supported upon a post 42, carried by a cross-beam 42^a at its 15 point of connection with a sill 44^a, which extends outwardly from the piano-casing and supports the keyboard. Mounted upon the shaft of the drum 37 is a gear-wheel 43, which is beveled and engages a bevel-gear 44, mounted upon a crank-shaft 45, journaled in the upper end of the post 42. Connected with the crank of the shaft 45 is a connecting-rod 46, which leads to the arm 47 of a rock-shaft 48, having a pedal 49 fixed thereon. Thus if 20 the pedal 49 be operated the shaft 45 will be rotated and the bow will be moved transversely of the string. In order that the shaft may be moved from its dead-center when starting the machine, the shaft has a ratchet-wheel 50 fixed thereon, and which is adapted for engagement by a push-rod 51, pivoted at its lower end to a bell-crank lever 52, attached at its lower end to a reciprocating rod 53, pivoted to a pivoted lever 54 in the form of the usual knee-swell employed upon an organ. The lever 54 is adapted for engagement by the knee of the operator, and thus when starting 30 the bow-operating mechanism this lever 54 may be moved to shift the ratchet-wheel 50 and carry the shaft off of its dead-center.

The strings 23 are normally held pressed back or retracted from the path of movement of the bow, as are also the strings of the treble, which are mounted upon the frames 34, and in order to hold the strings in this position an action is provided. This action is supported by the beam 42^a and a corresponding and parallel beam 56, these beams having the sills 44^a and 57 secured thereto and extending forwardly of the front of the casing of the piano and supporting the keyboard and its frame. The outer ends of the sills are connected by a beam 57^a.

In the beams 56 and 42^a are formed perforations, the corresponding perforations of the different beams being in alinement. These perforations are increased in diameter from their upper ends downwardly in the beams 42^a and 56, the perforation of the beam 42^a having disposed therein the pins 58, which are inserted in the lower ends of rocking supports 59, while the perforations in the beam 56 receive the pins 60 at the angles of angular levers 61, one element of each of the levers being continued 60 forwardly to form the keys 62 of the instru-

ment. Pivoted to the upper ends of the rockers 59 and lever 61 of each key is a presser-bar 63, which is adapted for engagement at its inner end with the corresponding string 23 of the piano. These push-bars 63 are held normally in their positions of engagement with the strings 23 by means of spring-fingers 64, one end of each of which is fixed in a cross-piece 65, supported upon an upright 66 at one end of the casing and a second upright 67 at the opposite end, and which uprights are mounted upon the sills 44^a and 57. The movable ends of the spring-fingers 64 are fixed to presser-blocks 68, the engaging surfaces of which are arc-shaped, as shown, and have a 80 rolling contact with the presser-bars. Thus as each key 62 is depressed the presser-bar connected therewith is drawn forwardly and the corresponding string is released and moves forward and into engagement with the bow, 85 the movement of which latter causes the string to vibrate and give forth its tone. The string-supporting frames 24 are also held normally retracted by means of push-bars 70, pivotally connected with the upper ends of rockers 71 90 and angular levers 72, the levers 72 carrying keys which extend out into the keyboard-frame. The lower ends of the rockers 71 have pins 74, which enter perforations in the beam 42^a, while the levers 72 have pins 75, which 95 enter perforations in the beam 56 and form pivotal bearings. The push-bars 70 are normally held projected against the frames 24 to hold them retracted by means of spring-fingers 76, attached at their outer ends to the 100 cross-beams 65 and having blocks 77 pivotally connected at their movable ends, these blocks 77 having arc-shaped engaging faces which bear upon the push rods or bars 70 and force them in the proper direction. Thus as 105 each of the keys upon the levers 72 is depressed the corresponding push rod or bar will be drawn outwardly and will release a string-carrying frame, which will be projected under the influence of its spring 34 and will 110 engage the bow. When the key is released, the spring-finger 76 will force the frame backwardly and out of its operative position.

It is of course desirable that means be provided for varying the loudness of the sound of 115 the instrument, and this result can be accomplished by varying the pressure of the bow upon the strings. In order to vary this pressure, two rods 80 and 81 are provided with parallel rollers 82 and 83, respectively, at 120 their outer ends, the rollers of each of the rods receiving one side of the bow between them. In order to reciprocate these rods 80 and 81 to move the engaged side of the bow toward or away from the strings, bell-crank 125 levers 84 and 85 are pivotally mounted upon the cross-beam 65 and are pivotally connected at one end to the rods 80 and 81. The opposite ends of the bell-crank levers are pivoted to the arms 86 and 87 of a U-shaped frame, 130

the web 88 of which is projected outwardly and lies beneath the keyboard-frame. A knee-lever 89 is pivoted to the frame of the instrument and has pivotal connection with the web 88, which latter has slideable movement in hangers 89^a. Thus by operation of the knee-lever 89 the rods 80 and 81 may be reciprocated to correspondingly move that side of the bow adjacent to the strings toward and away from the strings to vary the pressure between the bow and the strings.

With the above construction it will be seen that by operation of the pedal 49 the bow may be caused to travel transversely of the strings and that if the keys be then depressed the corresponding strings may be presented to the bow and will be vibrated by it and will give forth the corresponding tones, there being no jarring or other objectionable defects incident to the usual piano-action, which comprises hammers.

It will of course be understood that in practice the specific construction shown may be varied and that any suitable system of stringing may be employed, and also that a motor of any style may be used in place of the pedal for operating the bow.

Connected with the posts or uprights 66 and 67 are cross-pieces 90 and 91 at each end of the frame of the piano, and upon these cross-pieces are fixed beams 92 and 93, which extend longitudinally of the piano. These beams 92 and 93 carry pins 94 and 95, which enter slots in the rockers 59 and 71 and the upwardly-extending portions of the levers 61 and 72 and to hold these parts against lateral movement. Similar pins 95 are disposed in the beam 57 and enter slots in the keys 62 to hold them properly spaced, these pins having felt washers disposed at their bases to prevent any noise of the parts striking against the beam.

In Figs. 12 and 13 there is illustrated the method of forming the bow, and which method is as follows: On account of the length of the bow required it is of course impossible to form each strand of a single hair, and it is therefore necessary that the bow be built up of connected sections. In the formation of the bow a number of hairs are arranged side by side, the adjacent ends of the several hairs being passed into a sleeve 100, formed of rubber or other suitable material, and into the sleeve at each end is passed one end of the succeeding series of hairs, the first series being shown at 101 and the second series at 102. This operation is continued until a belt of the proper length is formed, the ends of the belt being then connected. A series of hairs 103 are laid upon a sleeve 100, and the ends of the hairs of this series are passed between the hairs of the series 101 and the hairs of the series 102. This same operation is performed at the next sleeve 105 and is continued entirely around the belt, the free ends of the first and last series being finally connected. Any number of

layers may be thus applied, the result being a belt having the proper width and thickness and with the joints of the sections all upon the inner side of the belt. After the belt has been thus made it is mounted upon its carrying-rollers, as above described.

What is claimed is—

1. A musical instrument comprising a bow, and means for operating it, a series of strings fixed at their ends and adapted to normally engage the bow, means for holding the strings from engagement with the bow, means for releasing the strings to permit them to engage the bow, a plurality of slideable frames, a string carried by each frame and movable therewith into and out of operative relation to the bow, and means for moving the frames.

2. A musical instrument comprising a bow, and means for operating it, a series of strings having their ends fixed and adapted to normally engage the bow, means for holding the strings out of engagement with the bow, means for releasing the strings to permit them to engage the bow, a series of slideable frames, a string mounted upon each frame, means tending to hold the frames with the strings in engagement with the bow, means for holding the frames with the strings out of engagement with the bow, and means for releasing the frames.

3. A musical instrument comprising a plurality of wires, a bow adapted to vibrate the wires, said wires being adapted to normally engage the bow, means engaging the strings to hold them normally from engagement with the bow, means for releasing the strings to permit them to lie against the bow, and means for moving the bow toward and away from the strings to vary the vibratory effect.

4. A musical instrument comprising a plurality of vibratory elements, a vibrator adapted for engagement with the vibratory elements, means for moving the vibratory elements into and out of engagement with the vibrator, and means for moving the vibrator toward and away from the vibratory elements to vary the vibratory effect.

5. In a musical instrument, the combination with a bow and means for operating it, of a plurality of wires adjacent the bow and adapted to normally engage the bow, said wires having their ends fixed, means for moving the wires between their ends from engagement with the bow, means for releasing the wires to permit them to engage the bow, and means for moving the bow toward and away from the wires.

6. In a musical instrument, the combination with a plurality of wires, of a bow adapted for engagement with the wires, reciprocating rods having rollers at their ends lying upon opposite sides of the bow and adjacent the ends of the latter, and a knee-lever connected with the rods for operating them.

7. A bow comprising a plurality of series

of hairs having their ends successively connected, and a second plurality of series of hairs, the hairs of the second series lying upon the connections of the first series and having their ends passed between the hairs of the first series and successively connected.

5 In testimony that I claim the foregoing as

my own I have hereto affixed my signature in the presence of two witnesses.

EDGAR L. HOLCOMBE.
